UNITED STATES PATENT OFFICE.

ALEXANDER R. SMITH, OF BROOKLYN, NEW YORK.

STALL-FLOOR.

SPECIFICATION forming part of Letters Patent No. 463,244, dated November 17, 1891.

Application filed January 9, 1891. Serial No. 377,247. (No model.)

To all whom it may concern:

Be it known that I, ALEXANDER R. SMITH, of Brooklyn, in the county of Kings, and in the State of New York, have invented certain new and useful Improvements in Drain-Floors for Stalls; and I do hereby declare that the following is a full, clear, and exact description thereof, reference being had to the accompanying drawings, in which—

10 Figure 1 shows a perspective view of my improved drain-floor for stalls in place; Fig. 2, a longitudinal section of the same on a plane passing between two of the slats; Fig. 3, a transverse section on line $x-x$ of Fig. 1; 15 Fig. 4, a similar section on line $y-y$ of Fig. 1; and Fig. 5, a detail view in side elevation of a portion of one of the slats, showing the locking pin or rod in place in the side groove therein.

20 Letters of like name and kind refer to like parts in each of the figures.

The object of my invention is to provide an improved drain-floor for stalls; and to this end my invention consists in the drain-floor, 25 in its combination with the surrounding flooring, and in the construction, arrangement, and combination of the parts of the drain-floor, as hereinafter specified.

The special purpose which I have had in 30 view has been to produce a drain-floor which, while being capable of securing the quick and thorough draining away of all water from the stall, so that the occupant of the latter will always have a dry surface to stand or rest 35 upon, will be simple and cheap in construction, not liable to get out of order or become disarranged during continued use, and will be capable of being put together or taken apart easily.

40 It has also been my purpose to so arrange and construct the device that, while the slats will be held most firmly and securely in place and prevented from warping, any one of said slats can be readily removed when worn and 45 replaced by another.

As will be seen from the drawings and the description hereinafter given, I have also in 50 my drain-floor provided for a water-tight joint or connection between the sides and upper or inner end of the base and the surrounding plain flooring which shall effectually pre-

vent any passage of liquid beyond said sides or end and under the flooring.

In the drawings, A A designate the plain flooring which surrounds the space to be occupied by the drain-floor to be described. Such flooring can be supported in any desired way, as by battens or timbers a a on its under side or by other supporting devices.

Within a rectangular space in the center 60 of the stall-flooring is situated the base B of my drain-floor, consisting of a plate, preferably of cast or wrought metal, having on its upper side the series of longitudinal ribs B' B' and a flange B², extending along its 65 sides and across its upper or inner end. As the plate, in order to secure the desired drainage, is to stand at an angle inclined downward and rearward toward the rear end of the stall, the ribs B' B' are, as 70 shown in the drawings, made diminishing in height toward the upper end of the plate in order that their upper edges may be in a horizontal plane or parallel to the plane of the surrounding flooring. The flange B² is pref- 75 erably made, as indicated in the drawings, higher than the ribs B' B', so that its upper edge will stand in a plane above that of the rib-edges. The plain flooring around the space occupied by the plate is provided with a projecting portion a', extending in over the flange, and has a groove a², which receives the upper portion of the latter. When the drain-floor 80 is put in place for use, it is my intention to white-lead this groove or the flange-top, or 85 both, as indicated at a³ in the drawings, so as to make a thoroughly water-tight joint. If desired, any suitable kind of cement can be used instead of the lead.

The ribs B' B' are so arranged and constructed with reference to each other and the flange along the sides of the plate as to leave between them alternate narrow spaces b b for gutters and wider rectangular ones b' b' for grooves to receive the strips or slats C C, of 95 wood or other material, to form the bearing-surface or tread of the drain-floor. The gutter-spaces b b, which are preferably made V-shaped in cross-section, but not necessarily so, should be arranged in such way that there 100 shall be one of them at each side of the plate along the inner side of the flange on the lat-

ter, as shown in the drawings. In the faces of the ribs, on opposite sides of the slat-receiving spaces or grooves, are the half-round grooves b^2 b^2 , running along the ribs in a direction parallel to their upper edges. Each slat, of a sufficient thickness to bring its upper face on a level with the surrounding plain flooring and having its under face inclined to correspond with the inclination of the base-plate B, has on its opposite sides shoulders c c , parallel with its upper face, to rest upon the upper edges of the ribs, and downwardly-extending lips c' c' along the outer edges of the shoulders, adapted to extend down into the adjoining gutters b b a short distance, so that all liquid running down the sides of the slats will be guided into said gutters and will not tend to get in between the under sides of the shoulders and the rib-edges. In the sides of the slats, below shoulders c c , are longitudinal half-round grooves c^2 c^2 , corresponding with those in the ribs and adapted to form with them round channels for the reception of the pins or key-rods D D, which when in place serve to lock and hold the slats securely down in the spaces between the ribs. For convenience in withdrawing the rods when desired the rear ends of the latter can be provided with the loops or eyes d, for the accommodation of which the ends of the slats can be recessed, as indicated at c^3 in the drawings. At the lower end of the base-plate the lower portions of the ribs and the bottoms of the gutters are extended outward and downward, so as to form lips c' to discharge the contents of the gutters clear of the plate edge into the main drain E, to be described. While I do not in the drawings show any support for the upper end and body of the base B, it will be understood that any desired form of foundation or support can be used. The water-tight joint which I secure between the surrounding flooring and the flange B² is intended to make the usual cement or water-proof bed for drain-floors unnecessary, as it will effectually prevent any water getting past the sides of the base-plate to the under side thereof. Battens or timbers can then be used for the plate to rest upon, made of the proper height to give the latter its desired rearward inclination. With the surrounding flooring engaging the flange B² no cement bed to hold the plate-supports or receive anchoring ribs or projections on the under side of the plate, as in drain-floors as heretofore made, is necessary. The connection between the flange and flooring tends to hold the plate in place. At its rear end said plate is shown as supported upon a cross-beam F, which also serves as a support for the forward or inner side of the transverse drain E, made, preferably, of cast or wrought iron and having a lip E' projecting forward under the discharge-lips c' c' on the rear ends of the longitudinal gutters on plate B. The front or inner edge of said lip E' is turned up, so as to prevent any liquid flowing from

the gutters from coming in contact with the beam F.

Along the opposite sides or edges of the drain are the flanges E² E², the one on the forward edge resting upon and fastened to the timber or beam F, and the other one being supported upon and fastened to another beam F', parallel to F. Any desired means of fastening can be employed. As shown, the flanges have screw-holes e e, through which screws can be driven into the supporting-beams. The part of the forward flange which projects under plate B is made plain and horizontal, its upper face being adapted to receive and support the under side of said plate, while along the rest of the flange on opposite sides of the drain-lip E' there is an upright rib E³, adapted to be engaged by a groove e' in the supporting cross pieces or battens a of the plain flooring. The flange along the rear edge of the drain is provided with a similar rib E⁴ to be received in a groove e² in the flooring at the rear of the drain.

The described rib-and-groove connection between the drain-flanges and the surrounding flooring is to secure a water-tight joint to prevent any liquid getting from the drain out under said flooring.

As in the case of the flange B² on the plate B and the receiving-grooves therefor, the grooves e' e² can be white-leaded or provided with cement, as indicated at e³, to insure the tightness of the joint.

Extending across the drain E on opposite sides of the plate B and resting upon the flanges along the drain edges are the cross-battens G G on the under side of the drain-cover G', whose forward and rear edges engage, respectively, the rear ends of slats C C and the forward edge of the flooring at the rear side of the drain. With the drain-cover thus supported above the flanges E² E² there will be a clear space left for liquid to run from the longitudinal gutters between the slats down into drain-lip E', and thence into the drain itself. Such cover, abutting at its rear against the flooring and at its front against the slat ends, as described, will securely hold the slats against being worked longitudinally rearward by the pawing of the occupant of the stall and will cover the eye ends of the pins or key-rods D D in the recesses c² c².

While I show the flooring on the rear side of the transverse drain as lower than that at the sides of the drain-floor, it is not and does not have to be lower than the plane of the under sides of the rear ends of the slats, as it must be when the latter, as in the case of drain-floors heretofore made, are held in the grooves in the base-plate in such manner that they have to be moved longitudinally in order to insert them in or remove them from their places.

With my drain-floor, the slats of which can be lifted directly upward from the holding-grooves when they are unlocked for removal,

the rear flooring needs only to be low enough to admit the insertion or drawing out of the pins or key-rods D D. It does not have to be so depressed for allowing clearance of the 5 slats as to make necessary holding-cleats to hold the drain-cover up against the ends of the slats when the latter are in place.

While the plate B is preferably made of cast-iron, because such material withstands 10 best the corrosive action of the liquid to which it would be exposed when used in a stall-drain, and is shown as made in one piece with the ribs and flange B², I desire it to be understood that I contemplate making it, where 15 desired, of other material, and constructing the flange or ribs separately and attaching them in any desired way to the body of the base. Said base can be thus built up in any desired way without departure from my 20 invention.

The manner of putting in place my drain-floor and its operation when in place will be easily understood from the foregoing description and the drawings.

25 The cross-drain is put in position with its flanges resting on the supporting-timbers therefor, and the base B is then put down with its rear end resting on the front flange of the drain and the beam supporting such flange and 30 its body and upper end supported in any desired way to give the base-plate the proper inclination. The lips at the rear ends of the longitudinal gutters then project beyond the drain-flange and into the space within the lip 35 or offset on the drain. The plain flooring of the stall is now put down, with its grooves engaging the flange B² on the sides and end of the base and the ribs along the outer edges of the transverse drain-flanges. The joints thus 40 made are rendered water-tight by being white-leaded or cemented. The slats are put in place in their respective grooves and locked therein by the pins or key-rods inserted in the corresponding grooves in the slat and rib 45 sides, and the transverse drain-cover is laid down so as to abut against the ends of the slats and the edge of the flooring at the rear side of the drain. During use of the stall with the drain-floor thus put in place any 50 liquid falling upon the floor will run off of the sides of the slats down into the longitudinal V-shaped gutters, from which it is discharged freely into the transverse drain. The downwardly-extending lips along the 55 shoulders on the slat sides and the inner edges of the portions of the plain flooring which overlap the flange B² at the sides of the plate insure a free delivery of the liquid down into the gutters and prevent its coming in contact 60 with the upper portions of the ribs or flange.

The offset or lip on the front or inner side of the transverse drain affords a receptacle for receiving and guiding the liquid from the gutters into the drain and secures the protection of the discharge-lips at the rear ends 65 of the gutters from injury when the drain is being cleaned out.

The slats locked down between the ribs on the plate by the pins or key-rods in the manner described cannot warp or get out of place, 70 while any one of them can be readily removed when worn if the rods on opposite sides of it are drawn out of the receiving-grooves in slats and ribs. The insertion of another slat in place of the worn one is a most 75 simple matter, the locking-rods being thrust back into position when the half-round grooves in the slat-sides coincide with those in the plate-ribs.

My drain-floor, constructed and arranged 80 as described and shown, is cheap, simple, and easily made and has its gutters and transverse drain easy of access for cleaning out and not liable to clog up. Its slats can be put in position or removed therefrom readily 85 and without making necessary the removal of the base-plate or the surrounding flooring, and they are securely held in place and prevented from warping by locking devices 90 easily manipulated to release or secure them at will.

With the water-tight connections between the surrounding flooring and the base-plate and transverse drain the stable or stall can be constructed without the usual cement or 95 other water-proof bed under the floor.

Having thus described my invention, what I claim is—

1. In combination with a drain-floor for stalls having a base provided along its sides 100 with a flange, the surrounding flooring grooved to receive such flange, substantially as and for the purpose shown.

2. In combination with a drain-floor for stalls having a base provided with a flange 105 along its sides and one end, the surrounding flooring grooved to receive the flange, substantially as and for the purpose set forth.

3. In combination with a drain-floor for stalls provided with a flange along its sides, 110 the surrounding flooring grooved to receive the flange, and a coating of water-proof material on the abutting faces of flange and groove, substantially as and for the purpose specified.

4. In a drain-floor, the base-plate having on its upper side a series of longitudinal ribs arranged to form alternate gutters and slat-receiving spaces, the faces of the ribs forming the sides of such spaces being upright 120 and provided with longitudinal grooves situated above their bottom, substantially as and for the purpose set forth.

5. In a drain-floor, the base-plate having on its upper side longitudinal ribs arranged 125 to leave between them alternate V-shaped and rectangular spaces to serve, respectively, as gutters and slat-receptacles, and provided with longitudinal grooves in their faces, which form the sides of such receptacles, 130 such grooves being situated above the bottoms of the slat-receiving spaces, substantially as and for the purpose described.

6. In combination with a suitable base

- having slat-receiving ribs provided with longitudinal grooves, the slats having portions adapted to be passed downward between the ribs and raised therefrom, provided with 5 grooves in their sides to correspond with those in the ribs, and locking-pieces to engage the rib and slat grooves, substantially as and for the purpose shown.
7. In combination with the base having 10 slat-receiving ribs provided with longitudinal grooves in their slat-engaging faces, the slats having portions adapted to be passed downward between the ribs and raised therefrom, provided with corresponding grooves in 15 their sides and recesses in their ends, and the locking rods or pins having suitable withdrawing-heads accommodated by the recesses in the slat ends, substantially as and for the purpose described.
- 20 8. In a drain-floor for stalls, in combination with the slatted and guttered part having downwardly and outwardly projecting discharging-lips at the outer ends of the gutters, the cross-drain having the lip pro-

jecting under and beyond the gutter-lips at 25 a distance below the same, and the flange on which the slatted and guttered part rests, substantially as and for the purpose described.

9. In combination with the transverse drain provided with upright ribs on its opposite 30 sides, the surrounding flooring having grooves to engage such ribs, substantially as and for the purpose shown.

10. In combination with the transverse drain provided with upright ribs on its opposite 35 sides, the surrounding flooring having grooves to engage such ribs, and a water-proof coating on the abutting faces of the grooves and ribs, substantially as and for the purpose set forth.

In testimony that I claim the foregoing I have hereunto set my hand this 16th day of December, 1890.

ALEXANDER R. SMITH.
